UNITED STATES PATENT OFFICE.

RICHARD BARTH, OF OKLAHOMA, OKLAHOMA TERRITORY.

FIRE-ESCAPE.

No. 857,513.

Specification of Letters Patent.

Patented June 18, 1907.

Application filed October 6, 1906. Serial No. 337,765.

To all whom it may concern:

Be it known that I, RICHARD BARTH, a citizen of the United States, residing in Oklahoma city, in the county of Oklahoma and Territory of Oklahoma, have invented a new and useful Improvement in Fire-Escapes, of which the following is a specification.

This invention relates to fire escapes and more particularly to flexible ladders adapted to be secured to the window-frame, the object being to provide very simple and efficient means for securing the ladder to the frame.

Another object of my invention is to provide a very strong and durable ladder formed of a single piece of rope.

Another object of my invention is to provide a fire escape which is very light so that it can be rolled up into a small package so that it can be readily carried from place to place.

With these objects in view, the invention consists in the novel features of construction, hereinafter fully described and pointed out in the claims.

In the drawings forming a part of this specification:—Figure 1 is a perspective view of my improved ladder showing it in position to be used. Fig. 2 is a detail sectional view of a portion of a wall and window frame showing my improved supporting means secured in place. Fig. 3 is a perspective view of the supporting means. Fig. 4 is a detail perspective view of the ladder, supporting loop. Fig. 5 is a detail perspective view of a portion of the ladder showing the manner of securing it to the loop. Fig. 6 is a detail perspective view of a portion of the ladder. Fig. 7 is a perspective view of the brace used in securing the bit in place.

In the drawing A indicates the wall and B the window frame of an ordinary building. A bit C is adapted to be secured through the frame under the sill into the wall by an ordinary brace D, in the usual manner. The bit C is provided with an opening C' in which is secured a ring C² to which is adapted to be secured a snap hook E carrying a chain F to the other end of which is secured a snap-hook G, which is adapted to be secured to the eye H', of the loop H, which has overlapping horizontal ends H² over which is knotted a rope I, the ends I', I², forming the sides of the ladder.

The end I' is brought over and looped at I³,

over the rope I² about every one foot, and then brought back and twisted at I⁴ then 55 looped around itself at I⁵ and then looped at I⁶ around the twisted portion I⁵. The end I² is then looped at I⁷ around the loop I³ so as to prevent the same from slipping, forming a flexible ladder out of a single piece of rope 60 which is very strong and durable.

From the foregoing description it will be readily seen that I have provided a very novel fire escape constructed of a rope ladder which is very simple and cheap in construction and one which is provided with supporting means which can be easily and quickly attached without any danger of it pulling out.

Having thus fully described my invention, 70 what I claim as new and desire to secure by Letters Patent is:—

1. The combination with a bit provided with a rung, of a chain connected to said rung carrying a loop having overlapping ends 75 and a rope knotted over said overlapping ends having its ends formed into a ladder for the purpose described.

2. In a fire escape, the combination with a bit adapted to be secured under the window 80 frame, of a chain connected to said bit carrying a loop with overlapping ends, and a rope knotted over said ends, the ends of the rope being formed into a ladder, for the purpose described.

3. In a fire escape, the combination with a loop adapted to be supported out a window, of a rope knotted over said loop, one end of the rope being looped over the other end and the other end being looped over said looped 90 portion to form a rung for the ladder, for the purpose described.

4. In a fire escape the combination with a loop having overlapping ends, of a rope knotted over said ends, one end of said rope being 95 looped around the other end at intervals to form rounds, then twisted and looped around itself, then looped around the twisted portion, and the other end being looped around the looped portion of the other end for the 100 purpose described.

RICHARD BARTH.
